UNITED STATES PATENT OFFICE.

ANDREW EPPLER, OF LYNN, MASSACHUSETTS, ASSIGNOR TO UNITED SHOE MACHINERY CORPORATION, OF PATERSON, NEW JERSEY, A CORPORATION OF NEW JERSEY.

WELT-BUTTING MACHINE.

1,411,481.

Specification of Letters Patent. Patented Apr. 4, 1922.

Application filed April 12, 1919. Serial No. 289,517.

To all whom it may concern:

Be it known that I, ANDREW EPPLER, a citizen of the United States, residing at Lynn, in the county of Essex and State of Massachusetts, have invented certain Improvements in Welt-Butting Machines, of which the following description, in connection with the accompanying drawings, is a specification, like reference characters on the drawings indicating like parts in the several figures.

This invention relates to machines for manufacturing welted boots and shoes and particularly to machines for cutting off the ends of the welts of boots and shoes. Such machines are designed to perfect the joint formed between the end portion of the welt and the outsole and are known in the art as welt butting machines.

Objects of the invention are to provide an improved machine organization which will facilitate removal of the excess of material at the end portions of the welt and which will so form the ends of the welt that an improved joint will be made between the end portions of the welt and the outsole.

Features of the invention consist in a novel organization of a continuously rotated cutter and means for supporting, locating and presenting the welt to the cutter, which, as shown, provides for shaving or planing off the ends of the welt a little at a time, as distinguished from prior machines which could only be operated to remove the entire welt end by a single stroke of a knife.

Another feature of the invention consists in a beater member associated with the knife which acts in advance of the operation of the cutter to compress and beat down the welt against the welt supporting means and preferably acts prior to each operation of the cutter in removing a shaving. As a result the welt end is permanently compressed and beaten in place upon the heel seat, enabling the cutter to make a cleaner cut and to effect the butting operation by the removal of less material than is the case where such beating and compressing is not effected. As shown, the beater comprises a yielding member mounted on the cutter carrier and having its free end urged outwardly into welt engaging position by centrifugal force due to rotation of the cutter carrier.

Another feature of the invention consists

in novel means for centering the welt end relatively to the knife which means consists, as shown herein, of a member having the form of a blade extending under the welt and provided with a notch in its end which is adapted to engage the stitches by which the welt is held to the shoe and to position the welt laterally for the operation of the cutter. Preferably the end of the notch is sharpened to enable stitches which extend too close to the heel seat to be cut by rearward movement of the shoe.

A still further feature of the invention consists in means for beveling the welt at such a transverse angle that the outer portion of the beveled end of the welt will have a longer taper than the inner portion so that a tighter joint between the end of the welt and the outsole may be formed than is possible when the inner and outer portions of the skived welt have the same taper or when the outer edge has a shorter taper than the inner edge, as has been practical heretofore. As shown herein, the blade which extends beneath the welt has its side portions downwardly and outwardly inclined so that when either the welt end at the inner or the outer side of the shoe is presented to the blade the outer edge portion of the welt will be relatively unsupported and will be forced down by the action of the knife and a longer taper will be formed upon it than upon the higher and inner edge portion of the welt. The beater contributes materially to the result of forcing the welt end into contact with the beveled face of the welt positioning member.

These and other features of the invention will appear more fully from the following detailed description when read in connection with the accompanying drawings and will be pointed out in the appended claims.

In the drawings,

Fig. 1 is a side elevation of a machine embodying this invention;

Fig. 2 is a perspective view showing the work positioning means with the work in position and the cutter about to act upon the welt end;

Fig. 3 is a detail of the blade which engages the shoe under the welt;

Fig. 4 is a perspective view showing a modified form of blade for beveling the two sides of the end of the welt at different

105

angles in accordance with a feature of this invention; and

Fig. 5 is a perspective view of the blade shown in Fig. 4.

5 In the drawings 2 represents the frame of the machine which may conveniently be secured to a bench or table. Journaled in the frame 2 is a shaft 4 upon which a rotary cutter carrier 6 is mounted, the shaft being 10 provided with a pulley 8 by which the cutter may be continuously driven through a suitable clutch from any suitable source of power. As shown the clutch is operated by a treadle rod 3, upward movement of which 15 turns a lever 5 on its fulcrum 7, causing the forward end of the lever 5 to be removed from engagement with a stop projection 9 of the clutch, allowing the clutch to become set and the cutter 6 to be driven continuously. When the treadle rod 3 is released by removal of the foot from the treadle, a spring 11 returns the end of the lever 5 into the path of the projection 9 and causes the clutch to be thrown out so that the cutters 20 are not operated when the machine is not in use. To guard against injury to the operative the cutter is preferably enclosed in a casing 10 which is open only at the bottom, and as a further protection to the operator 25 a flap 12 may be provided partially to close the opening in the casing. As shown the cutter carrier is provided with two knives 14 which act successively upon the work as the cutter carrier rotates, and in advance of 30 each knife is a resilient member 16 secured at one end to the rotary cutter carrier and having the other end adjacent to the cutting edge of the knife 14. The outer face of the member 16 is preferably substantially in the 35 path of rotation of the knife edge and the free end of the member is caused to move outwardly of the edge of the cutter by centrifugal force due to rotation of the cutter. When the work is presented to the knife the 40 free ends of the resilient member 16 are deflected inwardly to expose the cutting edge of the knife which will then act upon the work.

45 The shoe positioning mechanism comprises 50 a member 20 pivoted to the frame 2 at 22 and carrying at its upper end a blade 24 which projects forwardly and a rear abutment 26 against which the rear end of the shoe is positioned. The member 20 is 55 normally held by a spring 28 in forwardly and downwardly inclined position for presentation of the shoe to the positioning means 24, 26, a stop 30 being provided to limit the movement of the member 20 into 60 work receiving position. An adjustable stop 32 is provided for limiting the movement of the work positioning means into operative position. The stop may comprise a screw 32 (Fig. 1) having a milled head 34 65 and lock nut 36, the end of the screw 32

being arranged to be engaged by the rear face of the member 20.

The shoe is presented with the blade 24 extending beneath the end of the welt and the rear face of the shoe against the stop 26 which is arranged for adjustment longitudinally of the shoe and is held in position by a set screw 38 (Fig. 2). The blade 24 is also arranged for longitudinal adjustment in a groove in the member 20 by means of 75 a slot and a set screw 40. The blade 24 is preferably provided with graduations 25 to enable the blade to be set longitudinally of the shoe in such predetermined position that the portion of the blade extending forwardly of the abutment 26 will locate shoes of different sizes properly for the action of the cutters 14 and cause the welt to be beveled at the proper point longitudinally of the shoe. The forward or welt engaging 80 end of the blade may be formed as shown in Fig. 3. This end of the blade is provided with a notch 42 which is sharpened at its edges to serve as a stitch cutter in case the 85 stitches extend too far toward the end of the welt. The notch also, by engaging the stitches, serves to position the shoe laterally with respect to the blade 24 and the knife 14. After the shoe is positioned with the end 90 of the blade beneath the end of the welt and the rear face of the shoe against the abutment 26, further pressure of the shoe rearwardly tends to swing the member 20 about the pivot 22 and to bring the work into the field of operation of the knives 14, and as 95 soon as movement of the member 20 is arrested by the stop 32 the desired portion of the welt end will have been removed by the rapidly repeated action of the knives 14.

100 During this operation each of the members 16, as it comes into engagement with the end of the welt, serves to flatten the welt and hold it firmly against the blade 24 while at the same time it yields inwardly sufficiently to expose the cutting edge of the 105 blade 14 which accordingly removes a portion of the welt, a new portion being removed by each knife as it comes into operative relation to the work, and so on until the stop 32 limits further movement of the 110 work relatively to the knife, and the butting operation is completed on that end of the 115 welt. The operator then repeats the operation upon the welt end at the opposite side of the shoe. The member 26 extends laterally, as shown in Fig. 2, to serve as a suitable abutment for the work when either end of the welt is presented to the cutter.

120 The blade 24 may be given the formation shown in Fig. 5, in which case the end of the blade is not only beveled longitudinally but is also beveled laterally so that the inner edge of the welt is beveled at a greater angle than the outer edge of the welt. The beveled portion 46 of the blade 24 is operative when 125 130

the welt upon the right side of the shoe as presented by the operator is being treated, and as the welt end is pressed against the beveled portion 46 by the action of the member 16 the welt end is twisted slightly so that the knife skives it off at a lateral inclination, the portion of the welt having the longer taper being at the outer edge of the welt end opposite the longer tapered portion 10 of the face 46. When operating upon the opposite end of the welt the beveled face 48 of the blade 24 will of course be operative and will cause the other welt end to be beveled off also with its longer tapered portion 15 on the outside. The result of this operation of the faces 46, 48 is clearly shown in Fig. 4 of the drawing. It will be clear that when a sole is applied to the heel-seat of a shoe having the end portions of the welt 20 thus formed the portion of the welt having the longer taper is presented along the outer edge of the sole and that, therefore, the danger of an open joint appearing between the welt and the sole is eliminated.

Having thus described my invention, what I claim as new and desire to secure by Letters Patent of the United States is:

1. In a welt butting machine, the combination of a rotary cutter having a cutting edge arranged to extend across the welt throughout its width, and a beater arranged in advance of the cutter to treat the welt prior to the cutting action of the cutter.

2. In a welt butting machine, the combination of a knife adapted for continuous rotation, a blade arranged to extend beneath the welt end of a shoe, and a support for the blade arranged to permit upward and rearward movement of the blade to position the shoe relatively to the cutter.

3. In a welt butting machine, shoe positioning means comprising a back gage, and a member arranged to be inserted beneath the welt, said means being mounted for upward and rearward movement with a shoe positioned thereon, combined with a continuously running rotary cutter to which the shoe is fed by said upward and rearward movements to cause successive shavings to be removed from the welt end by the cutter.

4. In a welt butting machine, the combination of a single blade adapted to extend below the free portion of either end of the welt of a shoe, said blade having a notch in its end arranged to act upon the welt stitches to position either end of the welt relatively to the blade, and a butting knife above the welt and co-operating with the blade to bevel the welt end.

5. In a welt butting machine, a welt butting knife, and a member adapted to extend under the rear portion of either end of the welt and formed with a notch to receive the inseam stitches and to center the welt laterally relatively to the knife.

6. In a welt butting machine, a welt butting knife, a member adapted to extend under the rear end of the welt and formed with a notch to receive the inseam stitches and to center the welt laterally relatively to the knife, the edges of the notch being sharpened to cut any stitches extending toward the heel-seat into line with said member, and means for limiting the rearward movement of the shoe. 75

7. In a welt butting machine, a welt support arranged to hold the inner edge of the welt higher than the outer edge of the welt, and a butting knife acting substantially in the plane of the shoe bottom to skive off the 80 welt.

8. In a welt butting machine, the combination of a support adapted to extend under the end of the welt, and a knife arranged to skive off the portion of the welt 85 above the support, said knife and support being relatively positioned to cause the outer edge of the welt to be beveled with a longer taper than the inner edge of the welt.

9. In a machine of the class described, a 90 blade adapted to extend beneath the end of the welt of a welted shoe and having an end portion with an outwardly and downwardly inclined bevel and a butting knife arranged to act in the general plane of the blade, and means for relatively operating the blade and cutter to form the welt end with a bevel which is longer at the outer side of the shoe than at the inner side of the shoe. 95

10. In a welt butting machine, the combination of a rotary cutter having a fixed radius of movement, and a beater arranged in advance of the cutter to treat the welt prior to the cutting action of the cutter, said beater being yieldingly mounted and held 100 outwardly of the cutter edge by centrifugal force due to rotation of the cutter.

11. In a welt butting machine, the combination of a welt butting knife, a notched blade arranged to extend beneath one end of a welt attached to a shoe with the notch engaging the inseam to locate the shoe laterally, and an abutment extending laterally of the blade on each side thereof to form a rest for the end of the shoe when either end of the 110 welt is presented to the blade and to prevent longitudinal movement of the shoe while the notched blade prevents lateral movement. 115

12. In a welt butting machine, the combination of shoe positioning means comprising a rear abutment, and a member arranged to be inserted beneath the welt, said means being mounted for upward swinging movement with a shoe positioned thereon, with a cutter arranged to operate repeatedly on the welt as the shoe is fed by said upward swinging movements and to remove successive shavings from the welt end. 120

13. In a welt butting machine, the combi- 130

nation of a blade adapted to extend below the free end of the welt of a shoe having rearwardly converging surfaces which act upon the welt stitches to position the welt 5 centrally of the blade, and a butting knife above the welt and co-operating with the blade to bevel the welt ends.

14. In a machine of the class described, a blade adapted to extend beneath the end 10 of the welt of a welted shoe and having an end portion with an outwardly and down-

wardly inclined bevel at each side and a butting knife arranged to act in the general plane of the blade, and means for relatively operating the blade and cutter to form either 15 the right or left end of the welt with a bevel which is longer at the outer side of the shoe than at the inner side of the shoe.

In testimony whereof I have signed my name to this specification.

ANDREW EPPLER.
